UNITED STATES PATENT OFFICE

BENJAMIN LEWIS, OF WOODSIDE, AND WALTER JOSEPH, OF LONG ISLAND CITY,
NEW YORK

PIPE CLEANER

Application filed January 28, 1931. Serial No. 511,884.

This invention relates to pipe cleaners, and the principal object is to provide a novel and improved pipe cleaner over that shown and described in U. S. Letters Patent No. 5 1,078,253.

While the present invention is especially adapted for cleaning pipes leading from beer barrels to the faucets, it is equally applicable for cleaning pipes of soda water fountains, 10 boilers or any other pipes which may be coupled in pairs; and thus the present invention has the same general fields of utility as the patented structure just referred to,—but with additional possible utilizations, and, in 15 practically every case, with marked advantages, as will appear hereinafter.

According to said patent, a device is provided which may be readily connected with two faucets or other openings from two pipes 20 the ends of which may be coupled together, such device including means for then forcing a cleaning solution through the pipes first in one direction and then in the opposite direction. It has been found exceedingly diffi-

cult to maintain said solution exactly as predetermined, and to employ said solution as required in various situations, in a combination like that of the patented device, wherein a pair of inspection and fluid guiding cylinders are present in such relation to a valve and its associated solution-propelling means that the solution has to be placed initially in one or the other of said cylinders. One of the chief operating troubles encountered 35 is that if it is the pipe opposite the other cylinder than the one appointed for the first introduction of the solution which is the dirtier and hence to be principally or solely treated by surging the solution therethrough

40 back and forth, the solution must make a substantially complete circuit, that is, traverse both cylinders and both pipes, in every case, even where only one pipe is desired to be cleaned and is the pipe coupled to the other 45 cylinder.

Therefore, it is an important object of the invention to provide an arrangement to obviate the difficulty just mentioned; and an arrangement which, preferably, is able to be 50 operated by the selective use of compressed

air and water, the air merely to drive the solution first in one direction and then in the other through the pipe or pipes to be cleaned, and the water to further dilute the solution, or further dilute the same while driving the solution in a desired direction through such pipe or pipes—with the air and water, alone or jointly, employed in any sequence desired, to clean out the device of residual solution after a pipe cleaning operation. 53 63

Another important object of the invention is to provide an improved construction for the cylinder assembly, wherein the number of coupling elements between the end-plates of the cylinders and the side walls thereof, 65 which latter are preferably cylindrical glass tubes as in the patent aforesaid, is materially reduced, and wherein also the work of assembling the cylinders in the proper fluid-tight manner is made easier and sure. 70

Other objects and advantages of the invention will be hereinafter specifically pointed out, or will become apparent, as the specification proceeds.

With the above indicated objects in view, 75 the invention resides in certain novel constructions and combinations and arrangements of parts, clearly described in the following specification and fully illustrated in the accompanying drawings, which show an 80 embodiment of the invention as at present preferred.

In said drawings,

Fig. 1 is a top plan view of a pipe cleaner constructed in accordance with our invention, 85 and shown in connection with two beer pipes;

Fig. 2 is, on an enlarged scale, an end elevation of the cleaner, partially broken away and partially in section;

Fig. 3, also partially broken away and 90 partially in section, is a top plan view of the parts shown in Fig. 2;

Fig. 4 is a longitudinal vertical section, taken on substantially the line 4—4 of Fig. 3;

Fig. 5 is a horizontal section, taken on substantially the line 5—5 of Fig. 2; and 95

Fig. 6 is a transverse vertical section, taken on substantially the line 6—6 of Fig. 5.

In carrying out our invention, we employ two cylinders 10 and 11, preferably formed 100

from glass, and closed at their rear ends by identical metal caps 10' and 11'. These caps are joined by an integral cross-rib 12, and the general structure thereby established has 5 a pair of supporting legs 13.

Opening through the plates 10' and 11' into the respective cylinders, are integral, threaded nipples 14 and 15; the threads of these nipples taking manually removable nuts 16, 10 whereby there may be readily detachably secured in place a pair of hose nipples 17, which latter nipples may be connected by flexible tubes 18 and 19 with faucets 20 and 21.

In illustrating our invention, we have 15 shown the device in connection with beer pipes, the faucet 20 being connected with one end of a refrigerating coil 22 which extends to a barrel 23, and the other faucet 21 being connected to a refrigerating coil 24 20 leading to a barrel 25.

The front ends of the cylinders 10 and 11 are closed by a structure 26 including integrally a pair of caps 27 for the front cylinder ends, and a cruciform valve structure comprising 25 a main boss constituting a valve casting 28 for a valve 29, a drain port 30, a connection 31, to cylinder 10, a connection 32 to cylinder 11, and a feeder connection 33.

This feeder connection is immediately be- 30 low and in communication with a solution receiving auxiliary tank 34, having a removable cap 34a, and carrying, in addition to its bottom nipple 34b which screws down into valve casing 28 to line up the bore of said 35 nipple and the bore of the feeder connection 33 as shown best in Fig. 4, a pair of upper, oppositely directed, sidewise extended threaded nipples 34c and 34d. The nipple 34d has screwed thereon a faucet 35, which 40 faucet carries a threaded nipple 36. The threads of the nipples 34c and 36 take manually removable nuts 37, whereby there may be readily detachably secured in place a pair 45 of hose nipples 38 and 38'. The nipple 38 is internally threaded, and has screwed therein, as shown in Fig. 2, an air-cock 39 provided with a hose nipple 39'.

To the nipple 38' is connected a hose 40 to a suitable source of water supply, and to 50 the nipple 39' is connected a hose 41 leading to a suitable source of compressed air.

Reverting to the details of construction of the cruciform valve structure formed integrally as above described with the front cylinder caps 27, this structure, it will be observed, is easily and quickly opened up in all parts, by disassembling the associated fittings, partially or completely, for cleaning, whenever desired; each of the two connections 55 31 and 32 (Fig. 5) having removable screw-plugs 40 at their outer ends, the drain connection 30 leading to a threadedly connected and readily detachable drain spout 41, the 60 valve 29 itself being readily removable by 65 pulling forwardly on its handle 29a follow-

ing removal of a single nut 29b, and the auxiliary tank 34 being disengageable at its nipple 34b from the feeder connection 33.

The manner of assembly of the front structure 26 including the caps 27, with the rear plates or caps 10' and 11', to lock therebetween the glass cylinders 10 and 11, is also of extreme simplicity and reliability. According to the patented structure aforesaid, a number of exterior tie bolts are employed, 70 running lengthwise of the cylinders but exterior thereto, this due to the fact that the filling-plug for the cylinder in which as aforesaid the cleaning solution is inserted, is located in one of the end plates or caps for that cylinder. These exterior tie rods have been found very difficult to tighten up evenly. In the structure of the present invention, it will be noted that only a single tie rod 42 is used 75 for each cylinder, this rod extending inside the cylinder and axially thereof. As shown best in Figs. 4 and 5, each such rod is really only a very large or rather long bolt having a head 42a and having a threaded inner end to be screwed up into an internally threaded boss 26' on the rear of said structure 26 and located centrally of the appropriate front cylinder cap 27. This construction, as provided preferably with gaskets as shown at 80 43 in Fig. 4 and at 44 in Fig. 5, permits instantaneous tightening up of but a single bolt, thereby to surely and safely and easily close each cylinder in the desired fluid tight manner.

The importance of this improvement will 85 be immediately appreciated, it being noted, and more fully explained hereinafter, that the cleaning solution is never directly inserted in either one of the cylinders 10 and 11, but, instead, is always deposited, preparatory 90 to a use of the device, in auxiliary tank 34, simply as a result of temporarily removing the cap 34a.

The front structure 26 has a pair of legs 95 45, which, combine with the legs 13 on the rear structure to suitably space the device on and above any suitable support 45', in coaction with the rods 42 which rigidify the device longitudinally,—thus providing a 100 much lighter and a more satisfactory device throughout.

The valve 29, as shown best in Fig. 6, is 105 adapted to be thrown to either one of two positions; to open a passage from the tank 34 to the cylinder 10, meanwhile connecting the cylinder 11 with the drain spout 41, and to open a passage from the tank 34 to the cylinder 11, meanwhile connecting the cylinder 10 to said spout.

Preparatory to cleaning the pipes air may 110 be forced through the coils so as to drive the contents back into the barrels or receptacles 23 and 25, and then the ends 22' and 24' of the coils 22 and 24 will be disconnected from the respective barrels and cou- 115 120 125

pled together as shown in broken lines in Fig. 1.

A suitable cleaning solution will then be placed in the tank 34 and the valve 29 will be turned to connect the tank with the particular cylinder 10 or 11 which leads directly to the coil 22 or 24 needing cleaning most or through which for any reason it is desired first to send the cleaning solution. If the 10 cleaning solution is of the right strength, it may be sent around the circuit in the direction just indicated by compressed air, on properly opening the cock 39. If it is desired to dilute the solution incident to such 15 travel, water may be employed as the sole or partial propulsion fluid, by properly opening the faucet 35 or said faucet and the cock 39. The situation may always be checked visually through the glass cylinder or cylinders. If only one coil is to be cleaned, or 20 cleaned first because the dirtier, the fluid is sent through that cylinder and its connected coil, back and forth, as many times as necessary; the direction of fluid flow being 25 reversed, after complete passage in the previous direction either through the coil being now specially cleaned or through both coils, as the particular situation requires. Such reversal is accomplished by reversing the 30 valve 29 as shown in Fig. 6 from the position there illustrated in full lines to that shown in broken lines, or vice versa. When the coil or coils being treated are thoroughly cleansed, the water supply may be shut off, 35 if water is then being employed, and air admitted so as to drive the solution out of the coils. When desired, air and water may be alternately admitted so as to aerate the cleaning solution and assist in its action. With 40 the cleaning solution in the auxiliary tank provided by the present invention, the solution can be sent direct to either cylinder, at will, so that cleaning the coils may be had from either end of the circuit; thus avoiding 45 any necessity to lose the strength of the solution, as in a coil not particularly needing cleaning at the time, because of having to send the solution around the entire circuit following from the fact that the solution 50 originally has to be placed in the apparatus by direct and initial deposit in one cylinder or the other.

We claim:

55 A device for the purpose indicated comprising a duality of transparent walled cylinders, a valve carrying head in communication with said cylinders, a two-way valve in said head, the latter having a discharge spout and the valve being movable to place either cylinder in communication with said discharge spout, and a cleaning fluid container surmounting said cylinders and in communication at its lower end with said head, said valve placing said container in communication 60 with either cylinder when the opposite

cylinder is in communication with the discharge spout, said container having air and fluid supply connections adjacent its upper end and said cylinders having nipples at the ends remote from said head for connection to 70 circulating pipes to be cleaned.

In testimony whereof we hereby affix our signatures.

BENJAMIN LEWIS.
